UNITED STATES PATENT OFFICE.

FRED P. ANGELL, OF HUNTINGTON PARK, CALIFORNIA.

DOOR-OPERATING MECHANISM.

Application filed July 6, 1925. Serial No. 41,792.

The invention has reference to door controlling mechanism in which doors are opened and closed by means of an electric motor operating a series of gears, and crank and connecting rod appliances, the motor being started by means of a push button or equivalent electrical controlling switch, and automatically stopped independent of the starting switch at predetermined opened and closed positions of the doors, or any intermediate position between the doors when one or both are obstructed in their normal operative movement.

The present invention contemplates a door opening and closing mechanism in which the moving parts operate in a predetermined direction and the cranks for operating the doors make complete revolutions.

An important object of the present invention is the arrangement of a tripping device by which a driving gear may be thrown out of meshed connection with its co-operating gear and stop the further movement of said doors when colliding with an obstruction capable of counteracting said tripping device in either an inward or outward movement of the doors, and without injury to the operating mechanism and with little if any injury to the obstruction.

Another object of the invention is to provide a tripping mechanism capable of being adjusted to be operated at differing degrees of stress, as expedient.

Still another object of the invention is to so construct the tripping mechanism that when the operating mechanism for any reason has been stopped by the action of the trip, said mechanism may be readily started after a removal of the obstruction by restoring the trip to a normal position through the aid of a cord strung over a series of grooved sheaves and secured at one end to said trip.

Another object of the invention is to provide a simple, inexpensive and efficient breaking attachment whereby the centrifugal momentum of the motor may be reduced, the motor brought to a stop and prevent further movement of the door-controlling mechanism after the electrical current has been shut from the motor.

These and other objects and advantages will be comprehended in the following description of the construction and operation of the parts of my invention both separately and together as a whole, it being understood

that the illustrations show a typical working embodiment of the mechanism, and that various details in the arrangement and construction of the parts could be changed without detracting from the spirit or intent of my invention.

In the drawings forming a part of this specification, Figure 1 is a plan view of my improved door-operating mechanism with the doors to the limit of their outward movement.

Fig. 2 is a side elevation of Fig. 1 with the doors partially broken away, looking through the door-opening from the exterior.

Fig. 3 is a detail cross section of the door-operating mechanism looking toward the left from the line x' of Fig. 1, and shows the trip mechanism latched in operative position.

Fig. 4 is a similar view to Fig. 3, with the trip mechanism released and its supporting shaft and pinion disengaged from its gear-driven mechanism.

Fig. 5 is a detail elevation of a door crank-operating gear and shows spring pressure contacts bearing upon an intermittent electrical circuit control attached to said gear for stopping the operation of the doors at predetermined positions.

Fig. 6 is an inverse view of the gear shown in Fig. 5, together with its attached electrical circuit control.

Like marks of reference refer to corresponding or equivalent parts in the different views in which A, represents swinging hinged doors suspended by appropriate hinges 1, to the side posts B, and C is a cross-girt, (extending from post to post over the doors), to which the door-operating mechanism is mounted.

The base D of the operating mechanism is attached to the girt C by bolts or other suitable means and carries an electric motor E operated by an electrical current supplied through conducting wires leading from a generator for the purpose, in the usual manner for operating motors of the character. On the opposite corners of one side of said base D, vertical bearings 3 are provided in which the door-operating gearing 4 is journaled, the lower ends of the journals being fitted with oppositely-disposed cranks 5, from the ends of which longitudinally-adjustable connecting rods 6 operate arms 7 attached to the doors A.

For the purpose of more readily installing

the door-operating mechanism the arms 7 are provided with lateral adjusting means, which obviates the necessity for re-setting the arms on the doors to get accurate and necessary co-operation in their functioning with the cranks 5 of the operating mechanism.

As shown, the arms 7 are pivoted near their inner extremities on gudgeons 8 extending from offset portions of the bolt-attached bases 9, and are given lateral adjustment by means of side arranged set screws 10 operative through side wings 11 of base 9.

Extending upwardly from the base D in alignment with the bearings 3 are the two driving-shaft bearings 12, in which the driving shaft 13 is journalled. This shaft at either end carries a bevel pinion 14 adapted to drive the crank-operating gears 4, and between the bearings of this shaft it carries a large spur-gear 15 driven from a small spur pinion 16 adapted to be thrown in or out of mesh with the gear 15, as will be herein-after explained. The pinion 16 operates from a shaft 17, the opposite end of which is rotatably mounted in a bearing 18 of the base D. This shaft is prevented from end thrust in its bearing 18 in which it is both rotatably and pivotally mounted, and near its geared end is mounted in a laterally operative bearing 19. This shaft also carries a driven gear 20 operated by a pinion 21 of the motor E.

The bearing 19 as herein shown is formed with a longitudinal slot 22 through which a keeper pin 23 extends through eared extensions of a post 24 of the base D. The opposite end of the bearing is formed with a retaining notch and an offset depending lug 26, the arrangement of both said notch and lug being to engage a beveled upper end of a retaining post 27 attached to or forming a part of the base D. Extending from the base in close proximity to the post 27 a vertical tension post 28 is provided. This post extends through a slot in the bearing 19 and is fitted above said bearing with a coil spring 29 playing between said bearing and a screw-threaded adjusting wheel 30 screw-threaded on said post, the object of the parts being to normally retain the bearing 19 in locked engagement with the post 27 through the medium of the retaining notch 25, and to permit said bearing to disengage said post and slide rearwardly in its attachment with the post 24 and release the running contact of the gears 15 and 16, for purposes herein-after set forth, yet be prevented from disengagement with said post 24 through the medium of the retaining lug 26, or through the medium of the keeper-pin 23, in its operation through the slot 22, or both.

To the forward end of the bearing 19 a cord 28 is attached and operates over a

grooved sheave 30 mounted at the upper end of a curved arm extending from the base D. The cord 28 is trained over suitable sheaves and its free end is arranged to be readily accessible to a garage attendant or other person so that the bearing 19 and its associated parts may be pulled forward and the gears 15 and 16 be brought into meshed engagement should they become disengaged through counteracting influences.

Striding the shaft 17, clamping members forming a break 31 are provided. The members of this break are secured together by means of an adjusting bolt 32, and the lower end of the break bears upon the base D, the object of the break being to counteract the momentum of the operating mechanism as a whole when the doors are nearing the limit of their movements.

To one of the driving gears 4 the electrical controlling make and break mechanism for opening the doors is attached. This mechanism consists of an insulating disc 33 riveted or otherwise attached to the wheel and upon its under side an electrical conducting concentric notched plate 34 is secured. The plate 34 is formed with diametrically-opposite peripheral spaces, (only one side of which is shown in Fig. 2), and within the intervening spaces offset portions of the insulation 33 project so that the surface between the parts will be uniform with the plate 34.

On the base D two spring arms 35 are secured to an insulated base 36, the free ends of the springs carrying contact rolls 37 adapted to bear upon the race formed by the plate 34 and the insulation within the open spaces of said plate, as shown.

To each of the spring arms 35 an electrical conducting wire 2 is trained, the wires forming a part of the electrical communication from the motor and being broken only as the contact rolls 37 become insulated within the open portions of the plate 34 in the operation of the gears 4 when the cranks 5 are positioned at the limit of their throw in both the opening and closing of the doors. In Figs. 1 and 2 the electrical circuit from motive power is shown as broken as the contact rolls 37 become insulated at the opened position of the doors, the starting of the motor being effected by a circuit breaker of usual construction operated independent of the door-operating mechanism.

Having described the essential features in the construction of my improved door-opening and closing mechanism, I will now explain the operation of the same:

Assuming the doors A are fully opened, as shown in Figs. 1 and 2, at which positions the electrical current from the motor E has been broken by the insulation of the contact or make and break rolls 37 passing upon the off-set insulated parts of the disc 33 within

the spaces within the plate 34, and it is desired to close the doors, the attendant would first use the independent circuit breaker (hereinbefore referred to), which would 5 start the motor, causing the train of gears leading from the motor to the shaft 13, to rotate, the shaft, through the pinions 14, imparting motion to the gears 4, causing them to revolve in opposite directions owing 10 to their geared relation with the pinions 14 on the shaft 13.

The gears 4 in turn would revolve the cranks 5 and, through the medium of the connecting rods 6 with the arms 7 attached 15 to the doors, cause said doors to swing inward on their hinges to a closed position, at which position the cranks 5 would be at the inward limit of their throw and the contact rolls 37 would again be at neutral, or insulated, the motor stopped, and vice versa. 20

Assuming that the doors were being closed and a person was caught between the inwardly swinging edges of the same, the resistance would be imparted to the gearing 25 between the cranks 5 and the motor E. This being the case, owing to the driving gear 16 and its shaft 17 being mounted in the bearing 19 capable of lateral thrust, the motor-driven gear 16 would ride upon its driven gear 15 by overcoming the tension exerted by the spring 29 and slide away or disengage said gear 16 and stop further movement of the doors, said doors operating to stop their connection with the driving gears in 30 like manner should an obstruction be met in opening the doors sufficiently to counteract the tension of the spring aforesaid.

A re-starting of the doors is effected by a 40 person pulling upon the cord 28 and restoring the bearing 19 to a normal position with its detent 25 engaging the post 27 and its gear 16 in mesh with the gear 15.

In accordance with the provisions of the 45 patent statutes I have described the principle of the construction and method of operation of my improved door operating mechanism together with an embodiment thereof, for the purpose set forth, but I am aware that certain modifications may be resorted 50 to in carrying out my invention without departing from the spirit or sacrificing any of the advantages thereof.

Having, therefore, set forth my invention, 55 what I claim as new and desire to secure by Letters Patent, is:—

1. In a door operating mechanism, the combination with a motor and a gear train operated by said motor to open and close a pair of doors, of means to disengage or separate motor communication between said motor and said doors through the separation of one gear from another including a lateral movable bearing in which one of said gears is journaled, means to restore said gears into engagement after having been disengaged 60

and means to yieldingly retain said gears in engagement.

2. In a door operating mechanism, the combination with a motor and a gear train operated by said motor, to open and close a pair of doors, of means to disengage or separate motor communication between said motor and said doors through the separation of one gear from another including a lateral movable bearing in which one of said gears 70 is journaled, means to restore said gears into engagement, said last named means including a cord trained over grooved sheaves, one end of said cord being attached to said bearing the other end of said cord being 75 amenable to hand operation.

3. In a door operating mechanism, the combination with a motor and a gear train operated by said motor to open and close a pair of doors, of a shaft interposed in said gear train and carrying a gear of said train near each end thereof, said shaft at one end being pivotally journaled and the gear adjacent said end being in constant mesh with a gear of said train on the shaft of said motor, and the gear at the opposite end of the first named shaft being normally engaged with a gear operatively connected with the doors, said first named shaft at said opposite end being carried in a laterally movable bearing whereby said last two named gears may be disengaged from said train and to stop the motor operation of said doors, means to hold said laterally movable bearing in a normally operable position, and means to restore said last named bearing to a normally operable position after disengagement of said last named gears. 85

4. In a door operating mechanism, the combination with a motor and a gear train including a large spur gear to open and close a pair of doors, of a shaft interposed in said gear train and carrying a small spur pinion of said train at one end and adapted to disengageably mesh with said large spur gear, said shaft at its opposite end being pivotally mounted and near its pivot carrying another gear of said train in continuous engagement with a gear of said train on the shaft of said motor, said first named shaft at its end opposite its pivot being journaled in a lateral bearing, a support for one end of said bearing, said bearing being slidably pivoted on said support, a detent near the opposite end and on the under side of said bearing, a post adapted to engage said detent when said large spur gear and said pinion are in operative engagement, said bearing having a vertically disposed slot, a post extending through said slot, a nut threaded on the upper end of the post, a compression spring interposed between said bearing and said nut, a stop extension at the end of said bearing adjacent the detent adapted to engage said first named post 100

110

115

120

125

130

when said detent has been released from its engagement with said post, a cord attached at the end of said bearing near said extension, said pinion being adapted to disengage 5 from said large spur gear when a predetermined force restrains said spur gear, said cord adapted to replace said bearing in a normal position after said gears have been disengaged from one another.

10 5. In a door operating mechanism, the combination with a motor and a gear train operable by said motor to open and close a pair of doors, of a shaft journalled in a 15 slidable pivotal bearing at one end and carrying a gear of said train in constant operative contact with a gear of said train on the shaft of said motor and carrying at its opposite end a gear of said train adapted to disengageably mesh with another gear of 20 said train, said first named shaft near its end opposite its pivot in said train being mounted in a lateral bearing, a support rearwardly of and to one side of said last named gear, said bearing being slidably pivoted on 25 said support, a detent in said bearing on its forward under side, a post adapted to engage with said detent, a lip or stop depending from the forward end of said bearing adapted to engage said post when said bearing has 30 been elevated to release said detent, whereby said first named shaft may swing laterally at one end and permit a separation of the last two named gears, said bearing having an elongated slot, a threaded post extending 35 through said slot, said post being fixed at its lower end and having a threaded nut at its upper end, a compression coil spring inter-

posed between said bearing and said nut, a cord attached to the free end of said bearing, whereby said bearing may be replaced into 40 operative position after having been released from engagement with said first mentioned post.

6. In a door operating mechanism, the combination with a pair of doors, a revolubly 45 journalled crank mounted above each of said doors, means to revolve said cranks, an arm extending from each of said doors and a connecting-rod pivotally uniting the arm of a door with a crank journalled above said 50 door, said arms being capable of lateral adjustment in their attachment to said doors whereby said cranks, connecting-rods and arms will operate synchronous and in unison in opening or closing said doors. 55

7. In a door operating mechanism, the combination with a hinged door, a crank journalled above said door and means to actuate said crank, and a connecting-rod pivotally attached to the outer end of said 60 crank, of a base attached to said door, said base having an offset with oppositely disposed side lugs, a pivot extending from said offset, an arm pivotally mounted between its extremities on said pivot, adjusting screws 65 fitted through said side lugs and adapted to bear against the inner end of said arm whereby said arm may be moved on said pivot, said connecting-rod being pivotally attached to the outer end of said arm, whereby 70 a door may be adjusted in its operation with said arm.

FRED P. ANGELL.
